I. Brewster,

Churn.

Patented May 28. 1830.

X6003 (2) *James Brewster* (3) *Philadelphia, Pa.*
Scotia Patent

May 28, 1830

124

Number 6003 referred to in the Scotia Patent and making part of the same
containing a description in the words of the said James Brewster him-
self of his improvement in the Churn.

To all persons to whom these presents shall come, G. James Brewster of the
town of Philadelphia in the County of Philadelphia & State of New York doth
Gaveling -

Do it known that the said James Brewster have invented
a new and useful improvement not known or used before in the man-
ufacturing or extracting of Butter from Milk or Cream which
invention and the manner of using it is as follows.

This improvement in the Churn and the manufacturing making
or extracting of Butter from Milk or Cream consists in the machinery
which are attached to the barrel of the Churn to wit;

Two moveable standards are attached to the outside of the Churn near the
top - on the top of them a piece of wood is placed and connects them together
to the inside of one of them standards is attached a square block, which
together with the standard supports the horizontal shaft on which turns the
spare wheel which is turned with a crank: an upright shape piece in the
centre of the bottom of the Churn and turns in a box. The top end of this shape
goes through the piece placed over the standards or upright posts
vertically under this cross piece and on the shaft is attached a spur wheel
which catches into the face of the cog wheel - at the underside of the
face wheel another spur wheel meshes into the same wheel: this last
spur wheel is attached to the top of a circular block through this block a
spur wheel a circular hole is cut large enough to admit the shaft on
this shaft a shoulder is cut to support the block to this block are attached
two uprights one on the top and of a box or case form below the
same extending down near the sides of the Churn to near the bottom
of the side of same are attached to the uprights shafts to have with them

128. X6003

the outside set, in an opposite direction. The upper spine which is necessary
of yearly means of springs to stop the main shaft of meadow, in the gathering
of the butter. In which whereof I have herewith subscribed my name this

16 day of March 1830
